FIG. 5.

UNITED STATES PATENT OFFICE.

RUDOLPH BUCHNER, OF SYDNEY, NEW SOUTH WALES, AUSTRALIA.

PREPAYMENT MESSAGE RECEIVING AND DELIVERING DEVICE.

Application filed August 23, 1926, Serial No. 131,063, and in Australia August 25, 1925.

This invention relates to means for serving public convenience by holding and delivering messages at different locations. The object of the present invention is to provide an effective coin controlled device which may be set up in shops and other public places for receiving and holding messages and making such messages accessible to addressees who call for them. With such stations installed at prominent places in a city or town, one might leave at one or more of such places a message to be picked up at any later time by any person to whom it is directed, the sender and receiver having previously arranged to resort to the prearranged station or stations for the leaving and picking up of the message.

The device comprises essentially one or more tablets or receptacles provided with an automatic locking arrangement and a coin operated unlocking mechanism and with an indicator to display the names of addressees for whom memoranda have been left.

In an alternative arrangement a slot or other entry through which memoranda slips are insertible may be closed by a coin feed device when it is required to impose a charge for the leaving of a memorandum and another charge for the delivery of it. The memoranda cards or slips are collected in a box or filing arrangement and are accessible only when it is opened after release of the locking means by inserting a coin into a slot. The message receiving arrangements may include means for supplying memoranda cards or slips with or without payment therefor. In the former case, the insertion of a coin operates mechanism which permits access to a stock of cards or slips and which closes such access when a card or slip is inserted into a receiving drawer or slot. Cards or slips may then be taken only between the time when a coin has been inserted and a message has been placed in the box, and illicit access to the stock of cards or slips is thus preventable.

The indicator is a panel on which senders may write the name or initial or other indicator of their addressee so that a person expecting a message will have notice displayed that the expected message is awaiting him and he will not be obliged to make a payment for mere enquiry. On inserting the prede-

termined coin an addressee may gain access to the message and may then leave a reply message before reclosing the tablet or receptacle. The relocking is effected automatically.

The part of the indicator on which the name, initial, or other mark may be made by the person leaving a message is made accessible only whilst the message receiving device is open and it is at other times protected by a transparent cover. The writing of matter on the indicator by idle persons is thus guarded against.

The invention is not restricted to any particular structure of mechanism for the carrying out of the before-mentioned operations. One preferred form of it is hereinafter described, with reference to the accompanying drawings, and other arrangements are suggested in the following description.

In the accompanying drawings:—

Fig. 1 is an exterior view of the machine embodying the invention fitted with eight tablets, one of which is shown in the "out" position and the others in the "in" position. It is to be understood that machines may be made containing any required number of tablets arranged in one or more banks and that in place of tablets shallow drawers adapted to carry cards or envelopes may be fitted;

Fig. 2 is a vertical transverse section on the plane 2—2 Fig. 1;

Fig. 3 is a horizontal section on the plane 3—3 Fig. 2;

Fig. 4 is a partial transverse section on the plane 4—4 Fig. 3; and

Fig. 5 is a fragmentary perspective view explanatory of the lock releasing arrangement.

The external form of the casing may be adapted according to any "architectural" design, the cash register type of design indicated in the drawing being, however, a convenient one.

The casing 10 is completely closed except for the coin entry slot 11 and the slot spaces in which the drawers or tablets 12 are housed. It is preferred to make the tablets 12 of aluminium with a matt surface having the front edge 13 flanged downwardly to form an area on which addresses may be written. The tablets 12 are mounted on a pintle 14 on

which they may swing in horizontal planes. They are of quadrant shape and a detent 15 is formed in the arcuate edge of each of them; these detents are engaged by pawls 16 which are held up for engagement by back springs 17.

To enable the using of any tablet for a plurality of messages, the tablets may each carry a writing block with each leaf margin down-folded to hang as a flap over the front edge of the tablet. A message may be written on each sheet with the name of addressees on the sheet margin. A person resorting to the machine would in this case need to read all the overlapped address margins to trace a message left for him.

Each pawl 16 is provided with an offset tail 18 which sets behind a guide tube 19 in which a plunger 20 is slidable, 21 being a helical spring arranged for restoring the plunger to the out position. The exposed ends of the plunger project through guide holes in a face plate 22 on the front of the machine and their back ends are chisel shaped as shown at 23, Fig. 2. Through the guideways 19 extends a vertical guideway 24. In this vertical guideway a tier of slidable blocking pieces 25 are housed, resting one on top of the other, their lengths being so arranged that the top end of each one is at the level of the floor of one of the guideways 19. The guideway 24 which houses the blocking pieces 25 extends upwardly into another guideway 27 in which there is fitted a slidable plunger 28, the end 35 of which is chisel shaped as shown at 29. When the plunger 28 is at the in or idle position it checks upward movement of the blocking pieces 25 so that none of the plungers 20 can be pushed inward. When, however, the plunger 28 is retired, clearance is established for upward movement of the blocking pieces 25 sufficient to allow one of the plungers 20, but no more than one, to be pushed through its guideway 19. When one of the plungers 45 20 is thus pushed through its guideway 19, the check plunger 28 being first withdrawn, the striker piece 40 on the plunger which is so pushed in engages the offset tail 18 on the pawl 16 and retires that pawl to the dotted line position shown in Fig. 3. 41 is a spring acting through a bell crank lever 42-43 behind the offset tail 18 of the pawl 16 to force it to the locked position. The tablet or drawer 12 which is thus freed by retirement of its pawl 16 may then be swung outward from the in position shown in Fig. 3 to the out position which is shown in Fig. 1. When one tablet is thus swung out all the other tablets are held locked and none of these tablets can be swung open until the first one which has been opened is first closed. When pressure on the plunger 20 is removed the spring 21 acts to restore the plunger to the out position and allow the nose of the pawl 16 to bear against the arcuate edge of the tablet

or drawer 12 and to engage in a small depression 30 on the rear part of the arcuate edge 31. The light frictional engagement of the nose of the pawl in the locating notch 30 is sufficient to hold the tablet or drawer in the out position (Fig. 1) and to prevent accidental return of the tablet or drawer to the in position whilst a person is writing a message on the tablet or reading a message which has been written upon it. The tablet is forced outward as soon as its pawl 16 is released by means of a coiled wire spring 44. The tail of this spring bears against the side of the casing whilst its extended end 45 bears against a snug 46 on the underside of the tablet. The tablet in this construction must be closed home by manual action. It is opened automatically as soon as its plunger 20 is depressed. It is to be understood that a reverse arrangement may be adopted in which the spring 45 will be arranged to effect the closing movement as soon as the tablet 12 is released by a person who has placed a message on it or read a message from it, a dash pot or similar movement delay device being fitted to slow the closing movement in order that the tablet will not close suddenly whilst a person is using the machine if he momentarily ceases holding it open. In this case the user would need to swing out the tablet by manual action as soon as he had released the lock by depressing the plunger 20.

The bank of plungers 20, one relating to each tablet, is associated with the locking plunger 28 which works in the guideway 27 above referred to; that plunger is held normally in the closed position by means of a coiled spring 48 which has its abutment on a bracket piece 49. In its normal or locked position it sets above the top end of the tier of blocking pieces 25 and whilst it is in that position none of the plungers 20 can be moved inward to release the tablet. The locking plunger 28 is controlled by the coin mechanism. The mouth of the coin slot 11 leads into a coin runway 50; this runway may be fitted with any of the known devices for checking illicit interference by introducing wires or picking tools. 51 is a swing piece which is pivotally hung at 52 and forms the rear side of the bottom end of the coin slot 50. In the forward side of the coin slot 50 a push finger 53 is hung pivotally at 54 directly opposite the swing piece 51. A link 55 connects the push finger 53 with a master plunger 56 which is normally held in the out position by means of a coiled spring 57. In this normal out-position, clearance is offered for a coin of the appointed denomination to drop into the bottom of the coin slot 50. The coin is indicated at 156 as it would appear when inserted to effect the unlocking operation. 60 is a finger lever, the end of which takes under the coin 156; this lever is fulcrumed at 61 and its back end is connected by a link 62 to a

bracket member 63 which is fixed on the top end of the offset plate 43 which forms one arm of the bell crank lever which is controlled by the spring 41 as shown in Fig. 3. The axis 6 71 of this bell crank lever is journalled at 72 and 73 on the brackets 49 and 74 respectively. Upon a coin being inserted into the slot and coming to the bottom of the slot as shown at 156 Fig. 2, the lock releasing operation may 10 be performed. The master plunger 56 is depressed, thereby forcing the push finger 53 against the coin 156 and thus forcing over the swing piece 51 to the dotted line position. This movement does not liberate the coin for 15 the coin is still held resting on the finger 60, but it results in the withdrawal of the master bolt 28 from the full line to the dotted line position shown in Fig. 2, thereby liberating the blocking pieces 25 so that any one of the 20 plungers but not more than one of them may be depressed. When a plunger 20 is depressed its chisel end enters between the blocking pieces 25 so as thereby to block any other of the plungers 20 from being depressed. The 25 plunger 20 that is so depressed, however, operates simultaneously to release the pawl 16, whereupon the tablet 12 flies out to the position shown in Fig. 1 and swings back the bell crank 42—43. This swinging back movement 30 is communicated through the bracket 63 and the link 62 to the finger lever 60 so as to drop that finger, thereby removing the support from below the coin 156 and so allowing the coin to fall into the coin pocket 70. Immediately 35 the coin has fallen into the pocket 70 the spring 48 operates to force the swing piece 51, link 76 and master plunger 28 forward, thereby to lock the tier of blocking pieces 25 and prevent operation of any other of the 40 plungers 20 to release any one of the tablets 12. A person using the machine is thus obliged to insert a coin and operate the controls each time he requires to use one of the tablets or 45 drawers 12. A transparent protective door may be fitted to cover the front part of the casing in order to protect the address marginal portions 13 of the tablets from illicit interference; this protective door may be locked by any mechanism controlled by the 50 movement of the bell crank 42—43.

In the use of the device a person requiring to leave a message inserts a coin in the coin slot 11—50 then depresses the master plunger 56 and then depresses one of the plungers 20 55 corresponding with a tablet the margin of which is blank. Upon performing these operations the required tablet 12 is swung to the out position automatically by the action of the spring 45 and the coin is released and

deposited in the coin pocket 70 and the locks 60 then automatically reset. The person now writes his message on the face of the tablet 12 and writes the name of the addressee on the marginal portion 13 of the tablet. He then incloses the tablet which is immediately 65 locked by its pawl 16. If the tablet is made in drawer shape the message may be written on a card or placed in an envelope. When the addressee calls for the message and finds his name or call sign indicated on the marginal portion of one of the tablets, he inserts a coin in the coin slot 11—50, depresses first the master plunger 56 and then the plunger 20 corresponding with the tablet to which he requires to get access. The required tablet is then liberated and is swung to the open position by means of the spring 45 and the coin is liberated and deposited in the coin pocket 70. Having read the message the addressee obliterates it and restores the 80 panel to the closed position by swinging it back into its slot.

What I claim as my invention and desire to secure by Letters Patent is:—

1. A prepayment message receiving and delivering machine comprising a housing, a plurality of members adapted to carry memoranda and to expose the names of addressees and pivot-mounted to swing in a horizontal plane into and out of said housing, spring latches for automatically locking said members in the in-position, and means for releasing any one of said members but not more than one at a time, said means including manually operated plungers co-acting with said latches, and operable only when a coin is inserted in a coin slot in the housing. 85
2. A coin freed machine according to claim 1, in which the movable members are tablets having one surface of each of them prepared as a writing surface. 90
3. A coin freed machine according to claim 1, in which the movable members are receptacles adapted to carry cards or the like. 95
4. A coin freed machine according to claim 1, in which the movable members are formed with edge portions adapted to carry addresses in a permanently displayed position whilst said members are locked closed. 105
5. A coin freed machine according to claim 1, in which the movable members are formed with edge portions adapted to carry addresses in a permanently displayed position whilst said members are locked closed, and said edge portions are also prepared as 110 writing surfaces. 115

In testimony whereof I affix my signature.
RUDOLPH BUCHNER.
